UNITED STATES PATENT OFFICE.

HERBERT JAMES WOOD AND FREDERICK LYON EASTGATE, OF CHRISTCHURCH,
NEW ZEALAND.

AUTOMATIC VENTILATION-CONTROLLING APPARATUS.

Application filed April 29, 1924, Serial No. 709,744, and in New Zealand June 14, 1923.

This invention relates to means for automatically controlling the ventilation of buildings and rooms according to the internal temperature thereof, the object of the 5 invention being to provide simple, effective and reliable means of this nature.

In order that the nature of the invention and its construction may be clearly understood, reference will now be made to the accompanying sheet of drawings, in which:—

Fig. 1 is a sectional end elevation of a building such as a green-house equipped in accordance with the invention in its simplest form, and,

Fig. 2 is a sectional elevation of the apparatus employed to provide the mechanical movement necessary to actuate the ventilators or to govern such actuation.

Fig. 3 is a sectional detail view of a portion of the apparatus shown in Fig. 1; and

Fig. 4 is a plan view of the structure shown in Fig. 2.

For the purpose of illustrating the invention there is here shown in Fig. 1 a building 25 1 having a roof 2 in which are inserted ventilators 3 each consisting of a surface or louver-board pivotally mounted at or about its central line by means of a horizontal shaft or axis 4 upon which such louver-board may be turned so as to occupy a closed position, as here shown in full lines, or an open position as indicated in dotted lines or any intermediate position.

According to the present invention there 30 is provided and located within, or otherwise subject to the atmospheric temperature of the building, a closed vessel 5 containing atmospheric air or other gas capable of expansion and contraction in response to variations of temperature.

The invention includes also a vertically disposed vessel 6 having its upper end open and its lower end closed and in which vessel 45 is inserted a second vessel or bell 7 having its upper end closed and its lower end open and adapted to be sealed by means of water or other liquid contained in the vessel 6 to constitute a water-seal.

The interior of the bell 7 above its said 50 liquid-seal is in free communication with the contents of the aforementioned vessel 5, as by means of a pipe 8, the arrangement being such that an expansion of such contents will cause a portion thereof to be displaced from the vessel 5 through the pipe 8

to the bell 7 thereby causing the latter to rise in relation to the vessel 6, while a contraction of such contents of the vessel 5 will permit of a return displacement thereto from the bell 7.

It will be understood therefore that the vessel 7 will in this manner be caused to rise and fall in response to variations of pressure of the contents of the vessel 5 and which variations are in turn governed by the temperature surrounding the vessel 5.

In the preferred form of the construction the portion of the pipe 8 extending upward through the vessel 6 is surrounded, at a suitable interval, by a sleeve 9 which extends liquid-tight through the bottom of the vessel 6 and upward preferably to a point slightly above the liquid level, the upper end of such sleeve being sealed air-tight with the outer periphery of the pipe 8 while the lower end of such sleeve is open to the atmosphere. By this means therefore the said portion of the pipe 8 is separated from the said liquid contents by an annular air-space, thereby avoiding contact of the liquid with the said pipe and the consequent cooling action of such liquid upon the gas conveyed by such pipe.

In the simplest application of the invention the said rising and falling movement of the bell is harnessed to directly actuate the opening and closing movements of the ventilator.

Thus as shown in Fig. 1, there is attached to the bell 7, so as to rise and fall therewith, a vertically disposed rod 10 which is slidably received in a suitable guide 11 mounted stationarily in the building.

Carried by the rod 10 is a boss 12 to which are pivoted links 13 connecting with the ventilators 3, the arrangement being such that as the bell 7 rises in response to a rise in the temperature of the building such bell will, through the medium of the rod 10 and links 13, serve to open the ventilators thereby tending to reduce such temperature. Similarly in the event of the temperature of the building falling below a predetermined degree occurring while the ventilators are fully or partially open, the consequent sinking of the bell will permit such ventilators to close by gravity.

It will be understood that should the downward movement of the bell be arrested by the closing of the ventilator or ventila-

tors, a further fall in the temperature would tend to rarefy the gas in the system or produce a partial vacuum which might result in liquid from the liquid-seal being drawn 5 into the pipe 8.

In the preferred form of the invention therefore provision is made for permitting the bell after the closing of the ventilators has been accomplished to continue its downward movement independently of the ventilators.

As here shown this purpose is effected by making the said boss 12 slideable upon the rod 10 and providing the latter with a collar 14 adapted to be fixed in place upon such rod by a set-screw 15 or other means. The arrangement is such that as the rod is raised the collar will come in contact with the underside of the boss 12 and thus raise the latter in the required manner, and similarly as the rod is lowered this contact of the collar with the boss will govern the closing of the ventilator. When the ventilator is closed however, a further sinking of the bell will 25 carry the collar away from the boss which will depend from the links 13 while the rod slides to the required extent therethrough.

Suitable means are provided for arresting the opening movement when the ventilators 30 are fully opened, thus for example, as here shown, the boss 12 may be arranged, on reaching this position, to come in contact with the underside of the guide 11.

In the event of a further rise of temperature occurring after this upward limit of the movement has been reached the pressure of the gas contained in the system would in the ordinary course increase and thereby tend to cause such gas to force its way through the 40 liquid-seal and escape.

To overcome this difficulty, in the preferred form of the invention there is provided, and arranged in communication with the gas contained in the system, a chamber 45 the effective capacity of which is adapted to increase in response to pressure of such gas higher than that at which the said bell operates.

As here shown this chamber consists of an 50 annular vessel 16 inserted in the vessel 6 so as to loosely surround the bell 7. The said vessel is closed at its upper end while its lower end is open and sealed by the liquid contained in the vessel 6. The pipe 8 is 55 provided with a branch which extends upward through the bottom of the vessel 6 to the required height to connect with the space in the interior of the vessel 16 above the liquid-seal. The vessel 16 is loaded also as by 60 imposing thereon a suitable weight 17 which will be just sufficient to prevent such vessel from rising in response to the gas-pressure at which the bell operates.

The arrangement is such therefore that so 65 long as this normal pressure by the gas is

not exceeded the vessel 16 will remain in its lower position and will therefore exercise no influence or control, but in the event of a further expansion of the gas occurring when the bell has reached its upward limit the 70 vessel 16 will rise to the required extent to provide the necessary increase in containing capacity for the gas.

The gas contained in the said system may be at atmospheric pressure or at any suitable higher pressure.

The foregoing description of means for applying the movement of the bell 7 to effect or control the opening and closing of the ventilators is given by way of example and to illustrate one practical method of such application. If so desired therefore, any other suitable mechanical means may be substituted for the purpose.

We claim:—

1. An automatic ventilation system, comprising, in combination, a movable ventilator, a closed vessel containing an expandable fluid subject to variations of temperature, a stationary vertical vessel open at its upper end and closed at its lower end to contain a liquid, a bell disposed in said vessel and having its upper end closed and its lower end open and sealed by the liquid in the vessel, a pipe in communication with said fluid-containing vessel and the portion of said bell above the liquid in said stationary vessel, said pipe extending upwardly through the bottom of the liquid-containing vessel, a tube encircling said pipe and forming an annular chamber therearound, the upper end of said tube having a fluid-tight connection with the periphery of the pipe and a liquid-tight connection with the bottom of the liquid-containing vessel, the lower end of said tube being open to the atmosphere, and means for transmitting the movements of said bell to said ventilator.

2. An automatic ventilation system, comprising, in combination, a movable ventilator, a closed vessel containing a fluid subject to variations of temperature, a vertically disposed stationary vessel having its upper end open and its lower end closed to contain a liquid, a bell in said vessel having its upper end closed and its lower end open and sealed by the liquid in said vessel, communicating means between the interior of the fluid-containing vessel and the interior of said bell above said liquid seal thereby to cause said bell to rise and fall in response to the expansion and contraction of the fluid in said closed vessel, means for transmitting the movements of the bell to said ventilator, and means in communication with said fluid-containing vessel and adapted to absorb any internal pressure of said fluid higher than that necessary to operate said bell.

3. An automatic ventilation system, comprising, in combination, a movable ventila-

tor, a closed vessel containing a fluid subject to variations of temperature, a vertically disposed stationary vessel having its upper end open and its lower end closed to contain a liquid, a bell in said vessel having its upper end closed and its lower end open and sealed by the liquid in said vessel, communicating means between the interior of the fluid-containing vessel and the interior 10 of said bell above said liquid seal thereby to cause said bell to rise and fall in response to the expansion and contraction of the fluid in said closed vessel, means for transmitting the movements of the bell to said ventilator, 15 and an annular vessel in said liquid-contain-

ing vessel, said annular vessel encircling said bell and freely movable thereon, said annular vessel being fluid-tight at its upper end and having its open lower end sealed by the liquid in said liquid-containing vessel, said annular vessel being in communication with the fluid in said fluid-containing vessel and adapted to be raised by any internal pressure of said fluid higher than that necessary 25 to operate said bell.

In testimony whereof we have signed our names to this specification.

HERBERT JAMES WOOD.
FREDERICK LYON EASTGATE.
